HAIR CURLER

Henry Edward Watkins, Kew Gardens, N. Y.

Application June 17, 1948, Serial No. 33,597

4 Claims. (Cl. 132—40)

1

This invention relates to hair curlers.

An object of the present invention is to provide a hair curler with means preventing an undesired unwinding of a portion of a strand of hair from the hair curler.

A further object of the present invention is to provide a hair curler which may be readily manipulated.

Another object of the present invention is to improve on hair curlers as now ordinarily made. With the above and other objects of the invention in view, the invention consists in the novel construction, arrangement and combination of various elements and parts as set forth in the claims hereof, an embodiment of the same being described in the specification and being illustrated in the accompanying drawings forming part of this specification, wherein:

Fig. 1 is a side elevational view of a hair curler according to the invention.

Fig. 2 is a longitudinal sectional view of the hair curler shown in Fig. 1.

Fig. 3 is a right-hand end view of the hair curler shown in Fig. 1.

Fig. 4 is a left-hand end view of the hair curler shown in Fig. 1.

Fig. 5 is an elevational view of a blank to be used for the manufacture of a holding element of the hair curler shown in Fig. 1.

Fig. 6 is a perspective view of the holding element of the hair curler shown in Fig. 1, and

Fig. 7 is a right-hand end elevational view of the hair curler illustrating same in use.

Referring now to the drawings, 20 indicates a tubular body of a hair curler. The wall of said tubular body 20 is provided with a series of perforations.

The ends 24, 26 of a clamping wire 28 are pivotally engaged with bores 30 and 32 respectively in the wall of the tubular body 20. Preferably the clamping wire 28 is made of resilient material and is bent in such a manner at its portions 34, 36, that it is tightly held in its clamping position shown in full lines in the drawings wherein it is in engagement with the tubular body 20.

A stirrup-like holding element generally indicated by 38 has arms 40 and 42 opposite to each other. Said stirrup-like holding element 38 is made of a resilient material.

The arm 40 of said stirrup-like holding element 38 is in the shape of a cylindrical body split at 44 (see Figs. 4 and 6). Furthermore, the split resilient cylindrical body 40 is provided with an annular groove 46 arranged for engagement with

2

an annular indentation 48 of the tubular body 20. The arm 42 of the stirrup-like holding element 38 is in the shape of a strip extending outside the tubular body 20 substantially parallel to the longitudinal axis of said tubular body 20 at a distance from the outer wall thereof, when the holding element 38 is engaged with the tubular body 20. The end portion 50 of the arm 42 is bent towards the tubular body 20 and is in engagement with the latter at a point in a vertical plane beyond the vertical plane containing the end of the clamp 28 as viewed in Figs. 1 and 2.

In the embodiment shown in the drawings, the stirrup-like holding element 38 is made of an integral piece of material. A blank 38b as shown in Fig. 5 may be used for forming the stirrup-like holding element 38.

The cylindrical arm 40 of the stirrup-like holding element 38 is rotatably engaged with the bore of the tubular body 20. The arm 40 is prevented from axial displacement relative to the tubular body 20 by the engagement of its annular groove 46 with the annular indentation 48 of the tubular body 20. The intermediate portion 52 of the stirrup-holding element 38 connecting the arm 40 with the arm 42 is bent and shaped in such a way that, during a rotation of the stirrup-like holding element 38 relative to the tubular body 20, it clears the ends 24 and 26 of the clamping wire 28, which extend into the interior of the tubular body 20 to a certain extent.

As will be readily understood, the split resilient cylindrical body 40 having a slightly larger diameter than the bore of the tubular body 20 is in frictional engagement with the inner wall of said tubular body 20 whereby the holding element 38 and the tubular body 20 are held automatically in an adjusted position relative to each other. Furthermore, the abutting engagement of the end portion 50 of the resilient arm 42 with the tubular body 20 contributes to the holding of the stirrup-like holding element 38 and the tubular body 20 in an adjusted position relative to each other.

The hair curler shown in the drawings may be used in the following manner:

At first, the clamp is opened by swinging the clamping element 28 into the dash and dot line position 28' shown in Fig. 1. Thereafter, the end of a strand of hair is clamped between said clamping element 28 and the tubular body 20 by moving the clamping element 28 from its open position 28' into its clamping position 28 wherein it is held by the cooperation of the portions 34, 36 with the outer surface of the tubular body 20.

Now the stirrup-like holding element 38 is gripped by fingers of one hand and the tubular body 20 is rotated by fingers of the other hand relative to said stirrup-like holding element 38. During such a rotation of the tubular body 20, which may be readily carried out as the end portion 50 as well as the connecting portion 52 clear the ends of the clamping element 28, the strand of hair 54 is wound on the tubular body 20 as shown in Fig. 7.

Assume now, that at the end of the winding operation the various elements of the hair curler are in the position shown in Fig. 7 and that the stirrup-like holding element 38 occupies the position shown in full lines. Then the user of the hair curler holding the tubular body 20 in its prevailing position rotates the stirrup-like holding element 38 in counter-clockwise direction (as viewed in Fig. 7), until it reaches the dash and dot line position wherein its arm 42 being in the position 42' abuts against the scalp 56 of the user.

Now, the user of the hair curler may remove her fingers from the hair curler. The stirrup-like holding element is held in its adjusted position (shown in dash-and-dot lines in Fig. 7) relative to the tubular body 20 of the hair curler by the action of the split resilient cylindrical body 40 on the inner wall of the tubular body 20. Therefore, as the tubular body 20 is prevented from rotation relative to the stirrup-like holding element 38, an undesired unwinding of hair from the hair curler is eliminated.

As will be readily understood from above, the hair can be wound as tightly as desired and the wave impressed in the hair by the hair curler will start at the origin of the strand of hair.

I have described a preferred embodiment of my invention, but it is understood that this disclosure is for the purpose of illustration and that various omissions or changes in shape, proportion and arrangement of parts, as well as the substitution of equivalent elements for those, herein shown and described, may be made without departing from the spirit and scope of the invention as set forth in the appended claims.

What I claim is:

1. A hair curler comprising in combination: a tubular body adapted to have a strand of hair wound thereon, clamping means arranged on said tubular body for clamping the end of a strand of hair on the latter, and a stirrup-like holding element having arms opposite each other, one of said arms being in the shape of a cylindrical body inserted into the bore of said tubular body and rotatably engaged therewith, the other arm of said stirrup-like holding element extending outside said tubular body and being adapted to be brought into engagement with the scalp of a user, and said cylindrical body of the stirrup-like holding element being made of resilient material and being split whereby it holds said stirrup-like holding element and said tubular body in an adjusted position relative to each other.

2. A hair curler comprising in combination: a tubular body adapted to have a strand of hair wound thereon, clamping means arranged on said tubular body for clamping the end of a strand of hair on the latter, and a stirrup-like holding element having arms opposite each other, one of said arms being in the shape of a cylindrical body inserted into the bore of said tubular body and rotatably engaged therewith, the other arm of said stirrup-like holding element being in the shape of a strip extending outside said tubular body along a substantial length thereof and being adapted to be brought into engagement with the scalp of a user, and said cylindrical body of the stirrup-like holding element being made of resilient material and being split whereby it holds said stirrup-like holding element and said tubular body in an adjusted position relative to each other.

3. In a hair curler as claimed in claim 2, both arms of said stirrup-like holding element being made of resilient material, the main portion of said other arm of the stirrup-like holding element being spaced from said tubular body, and the end portion of said other arm abutting said tubular body.

4. A hair curler comprising in combination: a tubular body adapted to have a strand of hair wound thereon, a clamping element swingably mounted at one end of said tubular body for clamping the end of a strand of hair on said tubular body when brought into engaging position with the latter, holding means associated with said clamping means for holding same in said engaging position, and a stirrup-like holding element of resilient material having arms opposite each other, one of said arms being in the shape of a split cylindrical body inserted into the bore of said tubular body and rotatably engaged therewith, the other arm of said stirrup-like holding element being in the shape of a strip extending outside said tubular body and being adapted to be brought into engagement with the scalp of a user, the main portion of said other arm of the stirrup-like holding element being spaced from said tubular body, the end portion of said other arm abutting said tubular body at a point beyond the end of said clamping element, and said split resilient cylindrical body holding by frictional engagement with the inner wall of the tubular body said tubular body and said stirrup-like holding element in an adjusted position relative to each other.

HENRY EDWARD WATKINS.
